UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

TRIMMING APPARATUS OF TYPE-LINE-CASTING MACHINES.

1,055,302.

Specification of Letters Patent. Patented Mar. 4, 1913.

Application filed September 15, 1911. Serial No. 649,528.

To all whom it may concern:

Be it known that I, HEINRICH DEGENER, a subject of the German Emperor, residing at 26 Hollmannstrasse, Berlin, in the German Empire, have invented new and useful Improvements in the Trimming Apparatus of Type-Line-Casting Machines, of which the following is a specification.

This invention relates to the trimming apparatus of type line or type bar casting machines such as those known commercially under the trade mark "Linotype."

It has already been proposed to provide a plurality of pairs or sets of trimming knives capable of being turned as a single entity, about a vertical axis so as to present one or other of the said sets in position for trimming the cast type bars according to the particular body dimension of the respective type bar, the two knives of each pair being situated at a distance apart corresponding to the body dimension of the type bars to be trimmed by them and therefore of the mold in which the said type bars are cast, each pair of knives, in that respect, differing from the other pair or pairs. In that arrangement the substitution in operative position of one pair of knives for another pair was effected manually, and the object of the present invention is to provide for this substitution being effected automatically.

According to this invention, means are provided whereby each mold automatically brings the pair of knives appropriate to that mold into register therewith.

In the accompanying drawings:—Figure 1 is a front elevation partly broken away and partly in vertical section, of the improved devices; Fig. 2 is a view of the same partly in plan and partly in horizontal section, and Fig. 3 is a right-hand side elevation of part of the mechanism, showing the means for locking the different pairs of knives in their respective trimming positions.

The trimming knives 1, as previously stated, are mounted in pairs, the two knives of each pair being situated at a distance apart corresponding to the width of the mold in connection with which they are intended to be used, and as the slug is passed between them, its sides are trimmed by the outer edges of the knives in the usual manner.

The knives 1, of which, in the example illustrated, there are four pairs, are each of approximately triangular form in transverse section, and at their ends they are rigidly secured together by rings 3, 4 so as to form virtually a complete entity. The rings 3, 4 are each provided with a short vertical trunnion 5, 6 respectively, each of which is capable of rotating about a common vertical axis in the respective bearing 7, 8 fast to the machine frame. Below the bearing 8, the trunnion 6 has rigidly attached to it, a toothed wheel 9 and a locking head or collar 10, the latter provided with as many diametrical holes 11 as there are pairs of trimming knives 1, these holes, if desired, also extending through the trunnion 6.

12 is the rotating mold wheel carrying, in the example illustrated, two molds 13, 14, but there may be more than this number of molds on the wheel 12. The molds 13, 14, or more strictly speaking, the caps 13^a, 14^a thereof, each carry a pin or stud 15, 16 respectively each of which is at a different radial distance from the axis of the mold 80 wheel 12. The studs 15, 16 rotate with the mold wheel and are so positioned that, during their rotation, they engage with the vertical edge of a plate 17 which is capable of sliding horizontally in or on a stationary 85 guide 18, movement of the said plate in one direction being effected by a compression spring 19 and in the reverse direction (in opposition to the spring 19) by the action of the studs 15, 16 against the left-hand 90 edge of the plate 17. The sliding plate 17 has rigidly attached to it a toothed rack 20 in constant gear with the before-described wheel 9 so that as this plate is moved in or on its guide 18 it turns the knives 1 about 95 the axis of the trunnions 5, 6 to a corresponding extent.

As the studs 15, 16 are, as aforesaid, situated at different radial distances from the axis of the mold wheel 12, it is obvious that 100 as each mold is turned into the vertical position in front of the ejector 21, and at the back of the trimming knives 1, the latter will be turned about their pivotal axis to correspondingly varying extents which are 105 so determined that the particular knives 1 appertaining to the mold then in the ejecting position, are presented to the front of that mold.

In order to secure the knives 1 against 110

rotation when the type line is being forced between them, a locking pin 22, Fig. 3, is so arranged as to enter and engage with the particular hole 11 which, at the time, alines with it. This locking pin 22 is rigidly secured to a part of the machine which operates simultaneously with the ejection of the type bar, and preferably moves in a direction parallel with the axis of the mold wheel, for example it may be secured to the mold wheel slide 23. The forward end of the locking pin 22 is tapered so that it may freely enter the holes 11, and behind this tapered end it is of substantially the same diameter as that of the holes 11, so that, even if there be backlash between the teeth of the wheel 9 and the rack 20, this pin will serve both to accurately position the knives 1 and rigidly secure them against accidental displacement. During the next ensuing retraction of the mold wheel slide 23 the locking pin 22 is disengaged from the locking head 10 so as to leave the knives 1 free to be re-positioned by the appropriate stud 15 or 16.

Having thus described my invention, I declare that what I claim and desire to secure by Letters Patent is:—

1. In a type line casting machine, the combination with a plurality of pairs of trimming knives capable of being turned about a common axis and a mold wheel carrying a plurality of molds of different body dimensions, of means adapted to automatically turn the knives about the said axis to present to each mold brought into ejecting position a pair of knives of a corresponding body dimension.

2. In a type line casting machine, the combination with a plurality of pairs of trimming knives capable of being turned about a common axis, a rotating mold wheel, and a plurality of molds of different body dimensions on the mold wheel, of means on the mold wheel adapted to automatically turn the knives about the said axis to varying extents, to present to the respective molds pairs of knives differing in body dimension in accordance with the varying body dimensions of the said molds.

3. In a type line casting machine, the combination with a plurality of pairs of trimming knives capable of being turned about a common axis, a rotating mold wheel, and a plurality of molds carried by the mold wheel, of a plurality of studs carried by the mold wheel, at different radial distances from the axis of the latter, a gear wheel fast to the knives, a rack meshing with the gear wheel, and means operable by the studs to move the rack to varying extents.

4. In a type line casting machine, the combination with a plurality of pairs of trimming knives capable of being turned about a common axis, a mold wheel carrying

a plurality of molds and an organ moving in a direction parallel with the axis of the mold wheel, of a locking head fast to the knives and a device on the said organ adapted to engage with the locking head to secure the knives against rotation.

5. In a type line casting machine, the combination with a plurality of pairs of trimming knives capable of being turned about a common axis, a rotating mold wheel, and a plurality of molds of different body dimensions on the mold wheel, of means on the mold wheel adapted to automatically turn the knives about the said axis to varying extents, and means operative to temporarily lock the different pairs of knives in their respective trimming positions.

6. In a type line casting machine, the combination with a plurality of pairs of knives capable of being turned about a common axis, a rotating mold wheel, and a plurality of molds of different body dimensions on the mold wheel, of a plurality of studs on the mold wheel at different radial distances from the axis of the latter, a gear wheel fast to the knives, a rack meshing with the gear wheel, a plate carrying the rack, guides on which the said plate is free to slide and with which plate the studs on the mold wheel engage to move it in one direction, and power means acting on the plate to move it in the reverse direction.

7. In a type line casting machine, the combination with a plurality of pairs of knives capable of being turned about a common axis, a rotating mold wheel, and a plurality of molds of different body dimensions on the mold wheel, a plurality of studs on the mold wheel, at different radial distances from the axis of the latter, a gear wheel fast to the knives, a rack meshing with the gear wheel, and means operable by the studs to move the rack to varying extents, of an organ carrying the mold wheel and moving with it in a direction parallel with its axis, a locking head fast to the knives and a device on the said organ adapted to engage with the locking head to secure the knives against rotation.

8. In a type line casting machine, the combination with a plurality of pairs of knives capable of being turned about a common axis, a rotating mold wheel, and a plurality of molds of different body dimensions on the mold wheel, a plurality of studs on the mold wheel, at different radial distances from the axis of the latter, a gear wheel fast to the knives, a rack meshing with the gear wheel, a plate carrying the rack, guides in which the said plate is free to slide and with which the studs on the mold wheel engage to move it in one direction, and power means acting on the plate to move it in the reverse direction, of a locking head fast to the knives, an organ carrying the mold

wheel and moving with it in a direction parallel with its axis, and a device on the said organ adapted to engage with the locking head to secure the knives against rotation.

9. In a typographical machine, the combination of a plurality of movable molds, a corresponding plurality of sets of trimming knives, and means whereby the movement of a selected mold to operative position brings the corresponding set of trimming knives into operative position.

10. In a typographical machine, the combination of a plurality of movable molds, a corresponding plurality of sets of trimming knives, and means for simultaneously moving the selected mold and its corresponding set of knives into operative relation.

11. In a typographical machine, the combination of a plurality of sets of trimming knives, a corresponding plurality of devices for presenting the slug thereto, and means for simultaneously moving the selected de-

vice and its corresponding set of knives into operative relation.

12. In a typographical machine, the combination of a mold carrier provided with a plurality of molds, a corresponding plurality of sets of trimming knives therefor, and connections to the carrier whereby a selected mold and its corresponding set of trimming knives are brought into operative relation.

13. In a typographical machine, the combination of a mold wheel carrying a plurality of molds, a corresponding plurality of sets of trimming knives, and means whereby the rotary movement of the mold wheel brings a selected mold and its corresponding set of trimming knives into operative relation.

In witness whereof I have hereunto set my hand in the presence of two witnesses.

HEINRICH DEGENER.
